LIGHT DIMMER

Warren G. Grimes, Urbana, Ohio

Application April 19, 1943, Serial No. 483,619

12 Claims. (Cl. 240—8.16)

This invention relates to a light dimmer and has for an object to provide an improved light dimmer particularly useful for an electric lamp. The type of electrical lamp to which this invention is applied is shown as being a lamp for projecting light on an aircraft instrument board but the principles and details of this invention are equally applicable for a headlight, tail light, spot light, or flash light, or any other similar light where it is desired to control the amount of light that may be omitted from full brilliancy to a substantially complete dimout and to any desirable degree of brilliancy in between.

With the ordinary dimming arrangements for lights, it is usually possible to provide only one degree of dimming between full brilliancy and completely out.

With this invention it becomes possible to dim the light to which it is applied to any desired degree and to leave it at such desired degree of dimness until it is desired to change the amount of dimming to any other desired degree.

A further feature of this invention is that it provides a dimming arrangement whereby the amount of dimming is spread substantially throughout the major area of the lens, through which the light rays are projected and it serves to cut off some, but not all of the rays at the extreme outer rim of the lens in a progressive amount until the dim-out has progressed to a substantially completely out position. In this manner it distinguishes particularly from previous shutter arrangements as well as from previous iris type arrangements.

With the foregoing and other objects in view as will hereinafter become apparent, this invention includes the combinations, constructions, and arrangements of parts hereinafter set forth, disclosed, and illustrated on the accompanying drawings, wherein:

Figure 1 is a front elevational view of this light as applied to a lantern mounted on a support.

Fig. 2 is a side view of Fig. 1.

Fig. 3 is a top view of Fig. 1.

Fig. 4 is a partly sectional view longitudinally of the lantern to which the invention has been applied, showing some of the interior details.

Fig. 5 is an end view of the light showing the dimmer at the half way position.

Fig. 6 is a similar view with the dimmer in completely light out position.

Fig. 7 is a similar view with the dimmer in the full open position.

Fig. 8 is a sectional view on line 8—8 of Fig. 4.

Fig. 9 is a partly sectional view of the operating shell.

Fig. 10 is a partly sectional view of the lens holding ring.

Fig. 11 is an elevational view of the dimmer fingers advancing thread shell.

Fig. 12 is a sectional view of Fig. 11.

Fig. 13 is an end view of the dimmer fingers.

Fig. 14 is an elevational side view of the dimmer fingers, and

Fig. 15 is a sectional view on line 15—15 of Fig. 13.

There is shown at 10 the lantern to which this invention has been applied. As shown, this lantern 10 is secured by means of a bracket 11 to a base ring 12 so that it may be secured as by screws 13 to any suitable supported wall 14. At one end the lantern is provided with a switch arrangement consisting of buttons 14 although it will be understood that any conventional switching arrangement either in the lantern 10 or in the leads thereto from a separate power supply may equally be used. Although the lantern 10 is shown as mounted on a support 11 it may equally be applied to a portable lantern such as a hand flash light, as well as to fixed lanterns such as headlights, tail lights, and spot lights of an automobile or other vehicle. The lantern 10 consists of a base 15 in which is mounted a lamp bulb 19 in any suitable type of socket therein.

Secured on a recessed neck 16 at the lamp end of the base 15 is the dimmer finger advancing thread shell 17 shown in detail in Figs. 11 and 12. As shown in Figs. 11 and 12, this thread shell 17

35 is provided with multiple circumferentially recessed threads 18 terminating short of an outer lipped end 20 of the shell 17. The other ends of the threads 18 terminate in a reduced extended neck end 21. This neck end 21 is held on the reduced neck 16 by means of screws 22 extending through apertures 23 in the neck end 21 and secured in appropriately positioned screw holes in the base neck 16. Also secured by the same screws 22 is a ring 24 which fits over the extended neck end 21, this ring 24 being marked with suitable indicia such as the words "close" and "open" and arrows pointing in the proper direction.

40 Adapted to cooperate with the female threads 18 is a multiple male thread ring 25 provided with multiple male threads 26 which can advance longitudinally of the female threads 18 by being placed in position thereon over the reduced ring end 21. Secured to the male thread ring 25 as by soldering or other permanent fastening are the dimmer fingers 27 which extend

45

50

55

integrally through the rim 28 secured to the metal thread ring 25. The dimmer fingers 27 are substantially triangular in outline, being shaped as shown in Figs. 14 and 15. These fingers 27 are made of extremely flexible spring metal and their shape and size such that when pressed against a concave surface of appropriate diameter they will start bending toward each other and if pressed sufficiently far against the concave surface they will meet along their sides and points to form a complementary concave surface, and will separate a progressively gradual amount as the pressure of the concave surface thereagainst is reduced. It will also be observed that each of the spring fingers 27 is separated from each other 15 finger by a rectangular slot 30.

Surrounding the dimmer fingers 27 is a control shell 31 shown particularly in Fig. 9. This control shell is provided at one end with an internally extending flange 32, the internal diameter of the flange 32 being substantially identical with the external diameter of the ring end 21 of the female thread member 17, and is of lesser diameter than the indicating ring 24, thus serving when in removable position to be held in appropriate position against the edge of the indicating ring 24. The other end of the control shell 31 is provided with an internal shoulder 33 and terminates in a lens holding ring receiving rim 34. Between the flange 32 and the shoulder 33 the control shell 31 is provided with a plurality of internally extended longitudinal ridges 35 while the shell 31 is flattened as at 36 between the internally extending ridges 35.

It will be noted that there are as many ridges 35 as there are slots 30 between the spring fingers 27 and correspondingly as many flattened surfaces 36 as there are spring fingers 27. The ridges 35 extend slightly into the slots 30 to prevent rotary movement of the spring fingers 27 relative to the control shell 31 but permit relative longitudinal movement while at the same time the ridges 35 guide this longitudinal movement.

In Fig. 10 there is shown a lens holding ring 37 of such a diameter that it will just fit into the rim 34 or shell 31 and is provided with an internally extending flange 38 of sufficient diameter to abut against the convex surface of the lens 40. An externally projecting lip 41 is provided on the outer edge of the ring to abut against the end of the shell rim 34.

In operation, the lens end of the lantern is assembled as shown in Fig. 4. In assembling the dimmer of this invention, the spring fingers 27 are placed over the female thread members 17. A temporary cylinder of paper may be used if necessary to hold the spring fingers 27 open until they can be placed over the neck end 21 and cause the male threads 26 to cooperate with the female threads 18, causing the free ends of the spring fingers 27 to project beyond the female thread lip 20. Next, the assembled female thread and fingers are inserted into the control shell 31 with slots 30 in alignment with ridges 35 until the flange 32 of control shell 31 abuts against the shoulder at the end of the female thread ring 21. The indicator ring 24 is then placed over the female thread ring 21 and the screws 22 inserted through the properly aligned screw receiving apertures into the base 15. After the lamp 19 is in position in the lantern 10, the concave lens 40 is inserted through the open end of the control shell 31 and held in position by sliding the lens holding ring 37 into the end of the shell 31.

While this ring 37 may be held frictionally in place if desired, suitable securing means such as a screw 42 may be threaded therethrough to positively prevent accidental separation.

The amount of dimout is controlled by merely rotating the control shell 31 relative to the base 15 for it will be obvious that as the control shell 31 is rotated back and forth, the male thread member 25 is likewise rotated causing the co-operating male thread 26 to move the spring fingers 27 longitudinally of the control shell against the concave surface of the lens 40. The longitudinal movement of the fingers will be in proportion to the movement of the shell, thus advancing and holding the fingers at any position to provide any degree of dimness, or black-out as graphically illustrated in Figs. 5, 6 and 7.

While the device has been shown and the structure described in detail, it is obvious that this invention is not to be considered limited to the exact form disclosed, and that changes may be made therein within the scope of what is claimed without departing from the spirit of the invention.

Having thus set forth and disclosed the nature of this invention, what is claimed is:

1. A dimmer for a lantern comprising an annulus, a plurality of flexible wedge-shaped fingers extending from said annulus, means for progressively bending said fingers inwardly toward the axis of said annulus across the path of light from the lantern, said means including a concave lens surface against which said fingers are longitudinally movable to cause said fingers to bend inwardly toward each other as they are moved thereagainst.

2. A dimmer for a lantern comprising an annulus, a plurality of flexible wedge-shaped fingers extending from said annulus, means for progressively bending said fingers inwardly toward the axis of said annulus across the path of light from the lantern, said means including a concave lens surface against which said fingers are longitudinally movable to cause said fingers to bend inwardly toward each other as they are moved thereagainst, and means for moving said annulus with its extending fingers longitudinally of its axis toward and away from said concave lens surface.

3. A dimmer for a lantern comprising an annulus, a plurality of flexible wedge-shaped fingers extending from said annulus, means for progressively bending said fingers inwardly toward the axis of said annulus across the path of light from the lantern, said means including a concave lens surface against which said fingers are longitudinally movable to cause said fingers to bend inwardly toward each other as they are moved thereagainst, means for moving said annulus with its extending fingers longitudinally of its axis toward and away from said concave lens surface, said moving means including a cooperating thread means providing the axial movement of said annulus and its fingers.

4. A dimmer for a lantern comprising an annulus, a plurality of flexible wedge-shaped fingers extending from said annulus, means for progressively bending said fingers inwardly toward the axis of said annulus across the path of light from the lantern, said means including a concave lens surface against which said fingers are longitudinally movable to cause said fingers to bend inwardly toward each other as they are moved thereagainst, means for moving said annulus

with its extending fingers longitudinally of its axis toward and away from said concave lens surface, said moving means including a cooperating thread means, said cooperating thread means including a spirally movable part and a part that is non-movable relative to the lantern to thereby provide the axial movement of said annulus and its fingers.

5. A dimmer for a lantern comprising an annulus, a plurality of flexible wedge-shaped fingers extending from said annulus, means for progressively bending said fingers inwardly toward the axis of said annulus across the path of light from the lantern, said means including a concave lens surface against which said fingers are longitudinally movable to cause said fingers to bend inwardly toward each other as they are moved thereagainst, means for moving said annulus with its extending fingers longitudinally of its axis toward and away from said concave lens surface, said moving means including a cooperating thread means, said cooperating thread means including a spirally movable part and a part that is non-movable relative to the lantern thereby providing the axial movement of said annulus and its extending fingers, and a manually operable dimmer control means for causing movement of said cooperating thread means parts relative to each other.

6. A dimmer for a lantern comprising an annulus, a plurality of flexible wedge-shaped fingers extending from said annulus, means for progressively bending said fingers inwardly toward the axis of said annulus across the path of light from the lantern, said means including a concave lens surface against which said fingers are longitudinally movable to cause said fingers to bend inwardly toward each other as they are moved thereagainst, means for moving said annulus with its extending fingers longitudinally of its axis toward and away from said concave lens surface, said moving means including a cooperating thread means, said cooperating thread means including a spirally movable part and a part that is non-movable relative to the lantern thereby providing the axial movement of said annulus and its extending fingers, and a manually operable dimmer control means for causing movement of said cooperating thread means parts relative to each other, said dimmer control means including a shell encompassing said flexible fingers, said shell having trackways to guide said fingers in their axial movement.

7. A dimmer for a lantern comprising an annulus, a plurality of flexible wedge-shaped fingers extending from said annulus, means for progressively bending said fingers inwardly toward the axis of said annulus across the path of light from the lantern, said means including a concave lens surface against which said fingers are longitudinally movable to cause said fingers to bend inwardly toward each other as they are moved thereagainst, means for moving said annulus with its extending fingers longitudinally of its axis toward and away from said concave lens surface, said moving means including a cooperating thread means, said cooperating thread means including a spirally movable part and a part that is non-movable relative to the lantern thereby providing the axial movement of said annulus and its extending fingers, a manually operable dimmer control means for causing movement of said cooperating thread means parts

relative to each other, said dimmer control means including a shell encompassing said flexible fingers, said shell having trackways to guide said fingers in their axial movement, said shell being rotatably mounted relative to the lantern whereby rotation of the shell relative to the lantern provides the foregoing movements.

8. A dimmer for a lantern comprising an annulus, a plurality of flexible wedge-shaped fingers extending from said annulus, means for progressively curving said fingers inwardly toward the axis of said annulus across the path of light from the lantern, said means including a concave lens surface against which said fingers are longitudinally movable, means for moving said annulus longitudinally of its axis toward and away from said concave lens surface, said moving means including a cooperating thread means, said cooperating thread means including a spirally movable part and a part that is non-movable relative to the lantern, a dimmer control means, said dimmer control means including a shell encompassing said flexible fingers, said shell being rotatably mounted relative to the lantern, and guide means projecting interiorly of said shell and cooperating with said flexible fingers permitting longitudinal movement of said fingers relative to said shell but preventing rotary movement of said fingers relative to said shell.

30 9. A dimmer for a lantern comprising an annulus, a plurality of flexible wedge-shaped fingers extending from said annulus, means for progressively curving said fingers inwardly toward the axis of said annulus across the path of light from the lantern, said means including a concave lens surface against which said fingers are longitudinally movable, means for moving said annulus longitudinally of its axis toward and away from said concave lens surface, said moving means including a cooperating thread means, said cooperating thread means including a spirally movable part and a part that is non-movable relative to the lantern, a dimmer control means, said dimmer control means including a shell encompassing said flexible fingers, said shell being rotatably mounted relative to the lantern, guide means projecting interiorly of said shell and cooperating with said flexible fingers permitting longitudinal movement of said fingers relative to said shell but preventing rotary movement of said fingers relative to said shell, and a lens, of which said concave lens surface forms a part, mounted on said shell for rotation therewith.

55 10. A dimmer for a lantern comprising an annulus, a plurality of flexible, wedge-shaped fingers extending from said annulus, and means for progressively curving said fingers inwardly toward the axis of said annulus across the path of light from the lantern, said means including a concave lens surface against which said fingers are pressed, a dimmer control means, said dimmer control means including a shell encompassing said flexible fingers, said shell being rotatably mounted relative to the lantern, and a lens, of which said concave lens surface forms a part, mounted on said shell for rotation therewith, and means on said shell cooperating with said flexible fingers permitting longitudinal movement of said fingers relative to said shell against said concave lens surface but preventing rotary movement of said fingers relative to said shell.

70 11. A dimmer for a lantern comprising an annulus, a plurality of flexible wedge-shaped fingers extending from said annulus, and means for pro-

gressively curving said fingers inwardly toward the axis of said annulus across the path of light from the lantern, said means including a concave lens surface against which said fingers are pressed, and means for moving said annulus longitudinally of its axis toward and away from said concave lens surface, said moving means including a cooperating thread means, and a dimmer control means, said dimmer control means including a shell encompassing said flexible fingers, said shell being rotatably mounted relative to the lantern, and means on said shell cooperating with said flexible fingers permitting longitudinal movement of said fingers relative to said shell but preventing rotary movement of said fingers relative to said shell.

12. A dimmer for a lantern comprising an annulus, a plurality of flexible wedge-shaped fingers extending from said annulus, and means for

progressively curving said fingers inwardly toward the axis of said annulus across the path of light from the lantern, said means including a concave lens surface against which said fingers are pressed, and means for moving said annulus longitudinally of its axis toward and away from said concave lens surface, said moving means including a cooperating thread means, and a dimmer control means, said dimmer control means including a shell encompassing said flexible fingers, said shell being rotatably mounted relative to the lantern, and guide means projecting interiorly of said shell and cooperating with said flexible fingers permitting longitudinal movement of said fingers relative to said shell but preventing rotary movement of said fingers relative to said shell.

WARREN G. GRIMES.
